UNITED STATES PATENT OFFICE.

HARRY E. BOYD AND JOSEPH H. NEAL, OF AKRON, OHIO.

DESIGN FOR A TIRE.

44,050.

Specification for Design.

Patented May 20, 1913.

Application filed March 5, 1913. Serial No. 752,225. Term of patent 7 years.

To all whom it may concern:

Be it known that we, HARRY E. BOYD and JOSEPH H. NEAL, citizens of the United States, and residents of Akron, Summit county, Ohio, have invented a certain new, original, and ornamental Design for Tires, of which the following is a specification, reference being had to the accompanying drawings, forming part hereof.

In the drawings, Figure 1, is a plan view of a portion of the tread of a tire showing

our new design; and, Fig. 2, is a transverse sectional view of a portion of a tire on lines 2—2 of Fig. 1.

We claim:

The ornamental design for a tire, as shown.

HARRY E. BOYD.
JOSEPH H. NEAL.
